UNITED STATES PATENT OFFICE

JUSTIN F. WAIT, OF NEW YORK, N. Y., ASSIGNOR TO SUN OIL COMPANY, OF
PHILADELPHIA, PENNSYLVANIA, A CORPORATION OF NEW JERSEY

METHOD FOR TRANSFERRING HEAT

Application filed June 18, 1930. Serial No. 460,868.

This invention relates to an improved method and apparatus for transferring heat from a source to a point of use, and particularly relates to an improved method and apparatus for removing impurities from a metallic medium such as mercury, cadmium, zinc, or the like, the vapors of which are used to effect the heat transfer.

This application is a continuation in part 10 of my application Serial No. 48,987, filed August 8, 1925, which has matured into Patent No. 1,765,038, dated June 17, 1930, in which is claimed the apparatus disclosed therein.

15 Heretofore the transfer of heat through the medium of metallic vapors has been accomplished by various methods and by the use of various types of apparatus. While results of substantial practical value have been obtained, such methods and apparatus as have been used have not proved entirely satisfactory and have been open to numerous objections, chief among which are that the efficiency of the metallic vapors is decreased 20 by the presence of entrained metal and that the flow of the vapors is retarded by the accumulations of scale, oxide and other impurities present in the apparatus or carried into various parts thereof by the vapors.

30 It is the broad object of the invention to provide a method and apparatus for the utilization of metallic vapor as a heat transfer medium with maximum efficiency and subject to proper control, and by which the vapors 35 will be freed from entrained metal and from solid impurities, accumulation of which tends to retard the flow of the vapors.

Having indicated in a general way the nature and purpose of the invention, I will now 40 proceed to a detailed description thereof with reference to the accompanying drawing in which there is illustrated one form of apparatus which may be utilized for carrying out the method embodying my invention, although it will be understood that the practice of the method is not dependent upon the use of any particular form of apparatus.

In the drawing the figure is a diagrammatic 45 view of one form of apparatus constructed

in accordance with the invention, certain parts thereof being shown in section.

The apparatus, all parts of which are formed of an oxidizable metal such as iron, 55 consists essentially of a heating element comprising a chamber 2 from which depend fingers 4 within which are located vertical tubular partition members 6, communication between the spaces inside and outside the tubular members being afforded by passages 8 at 60 the bottoms thereof. The heating element, or heater, is suitably mounted in brick work and is adapted to be heated by the application of heat about fingers 4. The heating element is charged with metal, as mercury, 65 cadmium, zinc, etc., or mixtures thereof, to the level indicated by the broken line L. Upon application of heat, the metal circulates through the passages on the outside and inside of members 6 to and from the chamber 70 2, the generated metallic vapors passing outwardly through pipe 10. The heated metal circulating to and from the chamber 2 passes downwardly and upwardly in the fingers at high velocity, which velocity decreases on 75 the passage of the metal into the chamber, thus permitting settling out and flotation of solid impurities such as oxide, scale, etc., which may be mixed with the metal. An aperture 13, provided with a suitable closure, 80 is formed in the end of chamber 2 at a level permitting removal of impurities from the surface of the metal in the chamber.

The pipe 10, which leads from the top of chamber 2 and which serves as a passage 85 for metallic vapors therefrom, is connected to a vapor flow control device which consists of a chamber 14 into which, from its top, the end portion 12 of pipe 10 projects. From adjacent the top of chamber 14 a pipe 16 90 leads to a heat absorbing unit shown conventionally as a coil 18 located within a chamber 20 adapted to contain material to be heated which will absorb heat from the metallic vapors in the coil. From the bottom 95 of the chamber 14 a pipe 22 extends downwardly and upwardly, its end being connected to the bottom of a second chamber 24 provided with cooling fins 26. A pipe 27 joins the top of chamber 24 with a vacuum pump 100

29. A pipe 28 extending upwardly within chamber 24 connects it with a separator 30 the construction of which will be hereafter described. A connection 31 from the separator may be connected to a suitable pressure or vacuum producing device.

In the operation of the control device, the chamber 24 and pipe 22 are filled with a metal similar to that in the heating element, for example, mercury. The level of the metal in the chamber is controlled by the pipe 28 which acts as an overflow. The chamber 24 is positioned at a higher level than chamber 14 and the metal is prevented from flowing from chamber 24 to chamber 14 by maintaining a pressure in chamber 24 such that the liquid cannot rise in chamber 14 above the lower end of pipe 12. The desired pressure is maintained in chamber 24 by means such as the pump 29 attached to pipe 27. So long as the metal in chamber 24 is prevented from flowing into chamber 14, vapors issuing from pipe 12 will pass from chamber 14 to the coil 18. The vapors on entering chamber 14 will lose velocity and any entrained metal will be dropped therein. If it is desired to shut off the flow of vapors from pipe 12, this is accomplished by varying the pressure on the metal in chamber 24 which will cause it to flow into chamber 14 and form a liquid seal over the end of the pipe.

The metallic vapors which enter the heat exchange coil 18 are in part condensed therein and vapor and condensate flow from the coil through a pipe 32 to a separator 34, the construction of which will hereafter be described. An outlet 36 from the separator connects it with a condenser 38 from which condensate may flow through pipe 40 to another separator 42. The separators 30, 34 and 42 are joined by pipes 44 and pipe 46 with the heating element 2.

Joined to the heating element 2 by a pipe 48 is another separator 50 which is illustrated in section. This separator is similar to separators 30, 34, and 42 and will be described in detail, it being understood that the description applies to the other separators. The separator consists of a chamber 50 surrounded by a trough 52 formed by an upturned flange into which the flange of a cover 54 extends, the last named flange extending into mercury 56 in the trough to form a liquid seal. The cover 54 is normally held in its closed position by means of a wedge or the like whereby it may be removed for the purpose of cleaning the surface of the liquid metal in the separator. The separator receives liquid metal through pipe 58 from condenser 60 which is arranged to receive vapors through pipe 62 from the safety chamber 64. This latter consists of a closed chamber provided with an inlet pipe 68 communicating with pipe 10 and an overflow outlet

70 which determines the normal level of liquid metal, as mercury, therein. Normally the liquid metal in the chamber 64 acts as a seal over the end of pipe 68 for normal pressures in the apparatus. If, however, the 70 pressure becomes excessive, vapors will force through the liquid 66 and the pressure will be relieved. The vapors will be condensed in condenser 60 and the condensate, freed from impurities in the separator, returned 75 to the heater.

In the operation of the device it will be noted that all liquid entering the heater 2 comes from a separator in which is retained 80 the floating oxide or scale which accumulates. These impurities may be removed from time to time by skimming them from the surface of the liquid in the separator.

The use of metallic vapors for purposes of 85 heat exchange raises numerous difficulties due to several peculiar properties of the metallic media circulating in the systems in connection with the material and properties of the apparatus employed. While the following 90 discussion is directed primarily to mercury, similar actions and results occur in the cases of other metals such as cadmium, zinc, or the like.

In a system of the type described, and particularly a system subject to interrupted 95 operation, air is present in variable quantities, being present either at the initiation of the process or accumulated by leakage during 100 operation. One impurity which occurs is the oxide of the metal which is used as medium, in the case of mercury, mercuric or other oxide which forms under certain conditions and decomposes under others in various parts of the apparatus. A second source of 105 impurities arises from the action of the hot active, monatomic, metallic vapors upon the materials of which the apparatus is constructed, generally fairly readily oxidizable metals such as iron. Apparently the mercury 110 vapors, as well as the metal walls of the apparatus, at the high temperatures involved yield an electronic discharge which ionizes oxygen which thereby becomes sufficiently active to readily oxidize the metals of construction. The reaction is relatively intense and 115 positive under some conditions of operation and particularly when the system is held in imperfectly formed apparatus, under vacuum or when intermittent operation is involved or as when air is applied as at 72 120 to control the pressure. I do not wish to confine my claims to this exact explanation. The explanation offered is probably correct although subsequent scientific development 125 may disclose other reasons for the results so far observed.

Simultaneously with the above noted action of the mercury vapors oxygen enters through the pores of the metal, providing a source whereby oxidation of the metals of 130

construction is effected. During the boiling of the mercury there is a thin film of vapor between the metal and the liquid.

The oxidized products are continuously removed by bombardment of the heavy particles of mercury including those particles which condense against the wall of the structure. The high specific gravity of the mercury causes a very vigorous action on the apparatus because of the high kinetic energy of the mercury due to its mass and monatomic form. This action removes pieces of scale, siliceous matter and even iron from the bombarded surfaces. A further corrosive action appears to result from the penetration of portions of the surfaces by the monatomic metallic vapors at high temperatures.

In a metal vapor system, the effect of such impurities is very deleterious and their separation is a matter of difficulty. Apparently the solid impurities are highly dispersed and of a colloidal nature so that they are separated only with difficulty while at the same time they collect in restricted passages so as to tightly plug the apparatus. By the use of the separator which is disclosed, by virtue of its design, there is obtained a definite motion of the minute particles of liquid mercury which coagulate into larger particles which separate out from the non-liquid oxide and subdivided mercury particles which float. The described motion is primarily due to the kinetic energy of the metallic vapors as they flow from pipe 58 and impinge upon the surface of the liquid metal; and is secondarily due to the surging of the liquid during operation. The line 58 preferably enters chamber 50 tangentially so that flow of condensate may give a small but effective centrifugal action which further assists in separation of the heavier mercury or other liquid metallic particles from the less heavy oxide and other impurities. The drops of mercury enter the separator at high velocity and these particles which have high density bombard the collected mass. The motion and/or passage of drops through the mass causes continuous recovery of mercury admixed with oxides.

50 What I claim and desire to protect by Letters Patent is:

1. The method which includes vaporizing a metal, removing entrained liquid metal from the vapors, effecting condensation of a part of the vapors by the absorption of heat therefrom, separating the condensate from the vapors and separating impurities from the condensate by flotation.

60 2. The method which includes vaporizing a metal, removing entrained liquid metal from the vapors, effecting condensation of a part of the vapors by the absorption of heat therefrom, separating the condensate from

from the condensate by flotation, and returning the condensate to be vaporized.

3. The process which comprises heating a metallic liquid, forming monatomic gas, causing said gas to heat walls of a container 70 of said gas, condensing said gas, causing condensate to remove from said walls oxidation products which may result from the contact of gas with the walls in the presence of oxygen.

75 4. The process which comprises forming vapors of a metal, condensing said vapors, collecting condensate and oxide which may be produced by oxidation of the vapors, and separating condensate from oxide and again 80 forming vapors therefrom and withdrawing separated oxide from the system.

5. The method which includes vaporizing a metal to form monatomic vapors in an apparatus of oxidizable material whereby oxidation of the apparatus may occur, removing entrained liquid metal from the vapors, effecting condensation of a part of the vapors by the absorption of heat therefrom, separating the condensate from the vapors, and separating oxidation products from the condensate by flotation.

85 6. The method which includes vaporizing a metal to form monatomic vapors in an apparatus of oxidizable material whereby oxidation of the apparatus may occur, removing entrained liquid metal from the vapors, effecting condensation of a part of the vapors by the absorption of heat therefrom, separating the condensate from the vapors, separating oxidation products from the condensate by flotation, condensing vapors separated from the first mentioned condensate, and separating oxidation products from the condensate of the last mentioned vapors.

95 7. The process which comprises forming metallic vapors, condensing said vapors, collecting such condensate and solid impurities within a separator, causing rotation of the mass of condensate and impurities and so separating condensed metal from impurities.

100 8. The process which comprises heating a metallic liquid, forming monatomic gas, causing said gas to heat walls of a container of said gas, condensing said gas, causing condensate to remove from said walls oxidation products which may result from the contact of gas with the walls in the presence of oxygen, collecting said oxidation products and condensate at a surface of condensate and withdrawing portions of said oxidation products from said surface.

110 9. The process which comprises heating a metallic liquid, forming monatomic gas, causing said gas to heat walls of a container of said gas, condensing said gas, causing condensate to remove from said walls oxidation products which may result from the contact of gas with the walls in the presence of oxygen, collecting said oxidation products and

115 120 125 130 the remaining vapors, separating impurities

condensate at a surface of condensate and withdrawing portions of said oxidation products from said surface and applying heat to condensate separated from said oxidation products and forming monatomic gas therefrom.

5. 10. The method which comprises forming metallic vapors, condensing said vapors, collecting condensed particles and oxide which may be produced by oxidation of the vapors on a surface of liquid metal, causing motion of said surface and so agglomerating condensed particles, and forming vapors therefrom.
10. 15. The method which comprises forming metallic vapors, condensing said vapors, collecting condensed particles and oxide which may be produced by oxidation of the vapors on a surface of liquid metal, causing motion of said surface and so agglomerating condensed particles and forming vapors therefrom and withdrawing oxides.

In testimony of which invention, I have hereunto set my hand, at New York city, New York, on this 31st day of May, 1930.

JUSTIN F. WAIT.
